his atty.

UNITED STATES PATENT OFFICE.

CHARLES FASTINGER, OF POINT PLACE, OHIO.

RADIATOR.

1,321,515.

Specification of Letters Patent. Patented Nov. 11, 1919.

Application filed February 8, 1918. Serial No. 216,125.

To all whom it may concern:

Be it known that I, CHARLES FASTINGER, a German subject, and a resident of Point Place, in the county of Lucas and State of Ohio, have invented a certain new and useful Radiator; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

This invention relates to radiators, and particularly to those of the type adapted for use in automobiles in connection with the water cooling system for the internal combustion engines thereof.

The object of my invention is the provision of an improved radiator construction wherein a number of cell sections or units, each including a plurality of cells, are employed and adapted to be easily and quickly built up in different ways to increase or diminish the permissible flow of water through the radiator as desired, to suit the speed of circulation of water through the particular system to which applied, and also adapted to provide the radiator with a multiplicity of both horizontal and vertical water circulating channels. Further objects and advantages of the invention will be apparent from the following detailed description thereof.

While the invention, in its broader aspect, is capable of embodiment in numerous forms, a preferred embodiment thereof is illustrated in the accompanying drawings, in which—

Figure 1 is a front elevation of a radiator embodying the invention. Fig. 2 is an enlarged fragmentary front elevation partly in section of the radiator. Fig. 3 is an end elevation of one of the cell sections partly opened up. Fig. 4 is a perspective view of one of said sections, and Figs. 5 and 6 are views illustrating different arrangements of the cell sections from that illustrated in Fig. 2.

The radiator embodying my invention is composed of a plurality of air cell sections or units A, which are secured together in desired built-up relation and inclosed within the radiator casing B, which has water chambers at the top and bottom thereof with

which the inlet and outlet water passages of the circulating system respectively connect, as well understood in the art.

Each cell section A is composed of a single sheet or strip of sheet metal 1, which is shaped to form two adjoining cells a, a by bending the opposite end portions of the metal first up at right angles to form the outer side walls 2, 2 of the cells, thence inward at right angles to form the top walls 3, 3 of the respective cells, and thence downward at right angles to form the inner sides 4 of the respective cells, which sides flatwise abut each other and are disposed in central reentrant relation to the cell section with their free edges in contact with the bottom portion of the section centrally of its side edges, as shown.

The metal forming the bottom, top and outer side of each shell is pressed inward to form a longitudinally extending recess 5 in each of such sides with the edges of said recess restricted or drawn inward slightly with respect to the squared end portions 6 of the cells, thereby adapting the sections, when built one upon another and one at the side of another, to form both vertical and horizontal water circulating channels or passages 7 and 8, respectively, therebetween as best illustrated in Fig. 2. It is apparent that the squared end portions 6 of the sections abut flatwise against each other and that the seams therebetween are closed by dipping the assembled sections of a radiator 90 into liquid solder. The dipping of the assembled radiator sections in the solder not only secures the sections together in assembled form and seals the seams between the end portions 6 of the adjoining sections but 95 also solders the reentrant sides 4 of a section securely together and at their free edges to the side of the section with which they abut.

In the arrangement of the cell sections illustrated in Fig. 2 the sections are built up in horizontal form, that is, with the two cells of a section in transverse horizontal alinement, thus providing a vertical water passageway 7 for each pair of cells in a horizontal row, whereas if the cell sections are built up in vertical order, that is, with the cells thereof in transverse vertical alinement, a vertical water passage 7 will be provided for each vertical row of cells. It is thus apparent that the horizontal arrangement of the sections will lessen the permissible flow of water through the radiator by

one-half over the vertical arrangement of such cells so that in building up the sections of a radiator the desired flow of water therethrough should be borne in mind and the 5 sections arranged accordingly.

In Fig. 5 the sections are illustrated as being built up both in vertical and horizontal form so that one portion of the radiator may have twice the number of vertical 10 water passages to another vertically alined portion. In Fig. 6 the sections are built up in vertical form with the cells of one row vertically staggered with respect to the cells of the adjoining rows so that the water, in 15 passing downward through the passages between the rows, will be caused to take an undulatory course due to the registering of the edge portions of the side recesses 5 of one row of sections with the recesses of the 20 adjoining row. This arrangement also permits a greater capacity flow of water through the radiator, as the passages are not restricted by reason of the shallow edge portions of the side recesses of one row of 25 sections registering with the shallow edges of the edge portions of the side recesses of the adjoining row of sections.

It is evident with my radiator that should 30 a leak occur in any section thereof such section which forms a small part of the radiator may be removed and another section substituted therefor at little expense and without necessitating tearing down the entire radiator. It is also evident with the extension 35 of the reentrant tongue or portion 4 within a radiator section as a division wall for the two cells thereof that a more rapid conduction of the water heat to the air passing through said cells is effected than would 40 otherwise be the case.

I wish it understood that my invention is not limited to any specific construction, arrangement or form of the parts, as it is capable 45 of numerous modifications and changes without departing from the spirit of the claims.

Having thus described my invention,

what I claim as new, and desire to secure by Letters Patent, is—

1. A radiator section comprising a strip 50 of heat conducting material of sheet form having the opposite end portions thereof bent upward over and inward to form two transversely adjoining air cells with the inwardly bent portions coöperating to form 55 the dividing wall between the cells and extending substantially to the portion of the strip between the bent end portions thereof.

2. In a radiator, a plurality of sections each comprising a strip of heat conducting 60 material of sheet form having the opposite end portions thereof bent upward, over and inward with respect to each section to form two transversely adjoining air cells, with the end portions of said cells substantially 65 rectangular in cross-section and with the three outer sides of each cell recessed to form water passages between adjoining sections.

3. In a radiator, a plurality of sections co- 70 operating to form air cells and air passages, each section comprising a strip of heat conducting sheet metal shaped to form transversely adjoining air cells with the end portions of the metal plate flatwise abutting 75 to form the dividing wall between the cells of the section, the side walls of the section being longitudinally recessed intermediate their ends to provide water passages between the sections and the end portions of 80 the side walls of adjoining sections abutting to close the edges of said passages at the ends of the sections.

4. In a radiator, a plurality of sections each forming two air cells, the sections in 85 one horizontal row disposed flatwise with their cells in a common horizontal plane, and the sections of another row disposed edgewise to form two horizontal rows of 90 cells.

In testimony whereof, I have hereunto signed my name to this specification.

CHARLES FASTINGER.
